J. F. H. Deibel,

UNITED STATES PATENT OFFICE.

JOHN F. H. DEIBEL, OF CANTON, OHIO.

DOOR-FASTENER.

SPECIFICATION forming part of Letters Patent No. 670,854, dated March 26, 1901.

Application filed September 10, 1900. Serial No. 29,600. (No model.)

To all whom it may concern:

Be it known that I, JOHN F. H. DEIBEL, a citizen of the United States, residing at Canton, in the county of Stark and State of Ohio, 5 have invented new and useful Improvements in Door-Fasteners, of which the following is a specification.

My invention relates to a door-fastener adapted for use as a door-bolt or as a check 10 to hold the door partly ajar.

The construction of the improvement will be fully described hereinafter in connection with the accompanying drawings, which form 15 part of this specification, and its novel features will be defined in the appended claim.

In the drawings, Figure 1 is a vertical sectional view of a portion of a door with my improvement attached thereto. Fig. 2 is a sectional view of the fastener, taken at right 20 angles to Fig. 1. Fig. 3 is a view in perspective of the housing of the device, and Fig. 4 is a perspective view of the bolt detached.

The reference-numeral 1 designates the door, formed in its lower edge with a vertical 25 recess 2 to receive a housing 3, formed at its lower end with perforated ears 4 to facilitate the attachment of the housing to the lower edge of the door. One side of the housing is formed with a recess or offset 5, within which 30 is arranged a flat spring 6, the upper end of which is secured to the housing, while its free end is adapted to engage the teeth 7 of a bolt located within the housing. The upper portion 8 of the bolt is square in cross-section, formed with an elongated slot 9, through 35 which extends a rod 10, secured at its inner end to the spring 6. The lower portion 11 of the bolt is reduced to circular form in cross-section and is surrounded by a coiled spring 40 12, one end of which bears against the lower end of the squared portion 8 of the bolt and the other end against the bottom wall of the housing.

The housing 3 is formed at one side with an elongated slot 13 and an opening 14, which 45 register with similar slots 15 and openings 16 in the door, and a plate 16^a, secured to the door. The rod 10 extends through the openings 14 and 16, and a treadle 17, projecting from the bolt, extends through the slots 13 50 and 15.

When the device is to be used as a door-check, it is provided with a concavo-convex metallic plate 18, to the under surface of which is secured by a screw 19 a flexible 55 washer 20.

The utility and operation of the invention will be readily understood. The tendency of the spring 12 is to force the bolt upward to the position shown in Fig. 2. To lower the 60 bolt, it is only necessary to apply pressure to the treadle 17 to depress the bolt, the reengagement of the spring 6 serving to hold the bolt in its depressed position against the tension of the spring 12. 65

Having thus fully described my invention, what I claim as new, and desire to secure by Letters Patent, is—

A door-fastener, comprising a housing, fitting a recess in the edge of the door, and having a recess on its inner surface: a spring secured at one end within the recess of the housing: a rod secured to said spring, and extending through the housing and door: a bolt within the housing formed with an elongated slot and with rack-teeth: a treadle projecting from said bolt: and a spring surrounding the lower portion of said bolt. 70 75

In testimony whereof I affix my signature in presence of two witnesses.

JOHN F. H. DEIBEL.
